Primary Examiner — Freda S Nunn(74) *Attorney, Agent, or Firm* — Cahn & Samuels, LLP(57) **CLAIM**

We claim the ornamental design for a storage drive chassis, as shown and described.

DESCRIPTION

FIG. 1 is a perspective view of a storage drive chassis shown without storage drives;

FIG. 2 is a front view thereof;

FIG. 3 is a rear view thereof;

FIG. 4 is a bottom view thereof; and,

FIG. 5 is a right side view thereof, the left side view being a mirror image.

(Continued)

Color is not an integral part of the disclosed and claimed design.

Broken lines shown in the drawings represent environment only and form no part of the claimed design.

1 Claim, 5 Drawing Sheets
